ATTORNEY.

UNITED STATES PATENT OFFICE.

JACK R. DUNLAP, OF DALLAS, TEXAS.

DESIGN FOR A SIGNAL HOUSING AND SUPPORT.

52,235.

Specification for Design.

Patented July 30, 1918.

Application filed March 15, 1918. Serial No. 222,754. Term of patent 14 years.

To all whom it may concern:

Be it known that I, JACK R. DUNLAP, a citizen of the United States, residing at Dallas, in the county of Dallas and State of Texas, have invented a new, original, and ornamental Design for a Signal Housing and Support, of which the following is a specification, reference being had to the accompanying drawing, forming part thereof.

Figure 1 is a front view of a signal housing and support embodying the design, and Fig. 2 is a side view of the same.

I claim—

The ornamental design for a signal housing and support, as shown.

JACK R. DUNLAP.
